Attorney

UNITED STATES PATENT OFFICE.

EDWARD LEWIS BREBIS, OF PINGREE GROVE, ILLINOIS.

ADVERTISING-DISPLAY DEVICE.

Application filed April 17, 1926. Serial No. 102,726.

The present invention relates to a device for displaying advertisements of various kinds and aims to provide a device of this nature which is compact and convenient, 5 simple in its construction, inexpensive to manufacture, economically operable, efficient and reliable, not likely to easily become out of order, and otherwise well adapted to the purpose for which it is designed.

10 With the above and numerous other objects in view as will appear as the description proceeds, the invention resides in certain novel features of construction, and in the combination and arrangement of parts as 15 will be hereinafter more fully described and claimed.

In the drawing:—

Figure 1 is a front elevation of a device embodying the features of my invention, 20 Fig. 2 is another front elevation thereof with the transparent panel removed, Fig. 3 is a vertical section therethrough, Fig. 4 is a rear elevation thereof, Fig. 5 is an enlarged detail view showing 25 the ratchet mechanism, and

Fig. 6 is another view of the mechanism shown in Fig. 5.

Referring to the drawing in detail, it will be seen that the numeral 5 denotes a casing 30 which is divided by a partition 6 into a front compartment A and a rear compartment B. A transparent panel 7 is mounted to close the open end of the compartment A and is provided with bracket members 8 for holding display cards interiorly of the panel. These cards are adapted to be placed over the major portion of the panel as is indicated in Fig. 1, but a substantially triangular space 9 is left vacant.

40 A shaft 10 is fixed on the partition 6 to extend forwardly into the compartment A and has rotatable thereon a pair of disks 11 each of which are provided with openings 12, said openings being radially disposed

45 A ratchet 13 is fixed to each disk 11 to rotate about the shaft 10. The teeth of the ratchets are oppositely disposed. A cruciform lever 14 is mounted on the shaft 10 between the ratchets 13 and one end thereof

50 has a pin and slot connection 15 with a pitman 16 operable by a wheel 17 fixed on a drive shaft 18 journaled through the partition 6.

As the pitman 16 reciprocates, it imparts 55 oscillations to the cruciform lever 14. Spring pressed pawls 19 are mounted on the other

ends of the lever 14 and engage one with each ratchet 13. It will thus be seen that the disks 11 will be intermittently rotated in opposite directions for displaying alternately advertising matter carried thereon between the openings 12 through the transparency in space 9 heretofore referred to.

The advertising matter on the rear disk, of course, will be visible through an opening 12 in the forward disk when properly disposed. A spring pressed brake 20 is associated with the disks to prevent them from spinning freely after they have been actuated.

70 The shaft 18 is driven by a beveled gear 22 which is in mesh with a beveled pinion 23 on a shaft 24 journaled in bearings 25 and driven by a beveled gear 26 and a beveled pinion 27, the latter being fixed to a pulley 28 driven by a belt 29 or in any other suitable manner. It is preferable to provide a pair of incandescent bulbs 30 in the bottom of the compartment A for lighting up the advertising matter on the disks 11.

75 It is thought that the construction, operation, utility, and advantages of this invention will now be clearly understood without a more detailed description. The present embodiment of the invention has been disclosed in detail, since in actual practice, it attains the features of advantage enumerated as desirable in the statement of the invention and the above description. It is apparent that numerous changes in the details 80 of construction, and in the combination and arrangement of parts may be resorted to without departing from the spirit or scope of the invention as hereinafter claimed, or 85 sacrificing any of its advantages.

90 Having thus described my invention, what I claim as new is:—

1. In a display device, a casing, a shaft in the casing, a pair of disks rotatable on the shaft, one disk having openings to permit the portions of the other disk to be visible therethrough, a transparency associated with the casing, and permitting visibility to certain portions of the disks, a ratchet on each disk having its teeth disposed in opposite directions, a lever rotatable on the shaft and between the ratchets, spring pressed dogs on the lever engaging the ratchets, and means for oscillating the lever.

100 2. In a display device, a casing, a shaft in the casing, a pair of disks rotatable on the shaft, one disk having openings to permit

the portions of the other disk to be visible therethrough, a transparency associated with the casing, and permitting visibility to certain portions of the disks, a ratchet on each disk having its teeth disposed in opposite directions, a lever rotatable on the shaft and between the ratchets, spring pressed dogs on the lever engaging the ratchets, a pitman, a pin and slot connection between the pitman

and the lever, a wheel eccentrically engaged with the pitman, a shaft for the wheel, a gear on the second shaft, a third shaft journaled in the casing, a pinion on the third shaft meshing with the gear, and means for rotating the third shaft. 10

15 In testimony whereof I affix my signature.

EDWARD L. BREBIS.
